UNITED STATES PATENT OFFICE.

MICHAEL MILAZZO, OF PITTSTON, PENNSYLVANIA.

ASH GUARD.

Application filed June 17, 1925. Serial No. 37,744.

The invention has for its object to provide a simple and efficient structure readily mountable in cooperation with the ash doorway of a stove to be used either as a substitute for or in cooperation with the door of that doorway, and for the purpose of guarding against inadvertent discharge of ashes from said doorway.

With the above and other objects in view that will hereinafter appear, the invention further resides in the novel details of construction, combination and arrangement of parts, all of which will be first fully described, then be particularly pointed out in the appended claims, reference being had to the accompanying drawing, in which:—

Figure 1 is a perspective view illustrating the invention in use.

Figure 2 is a vertical cross section showing the invention mounted in an ash doorway.

Figure 3 is a detail perspective view of the invention.

Figure 4 is a diagrammatic plan view illustrating the blank from which the invention may be formed.

In the drawings, in which like numerals of reference indicate like parts in all the figures, 1 indicates the front or main body portion of the ash gate, which includes the abutment extension 2, and 3 the side wings, curved as at 4 to facilitate swinging movement as later described, and which are provided with abutment shoulders 5, the purpose of which will also presently appear.

While the device may be made of cast iron and have its front face nickel plated to enable its use as a substitute for the ash door, it is preferably used in cooperation with such a door and stamped from a metal blank, as indicated in Figure 4 and shaped to the form indicated in Figures 1 and 3.

The structure of my improved gate and the manner of mounting the same are such that it may be used in cooperation with the ash door in a manner rendering interference therewith unnecessary.

When formed as indicated in Figure 4, the body includes extended ears 6 adapted to be shaped as at 7 to loosely receive or surround the hinge pintle 8 and be securely riveted as at 9 so as to provide a pivoted bearing for the body thereon.

The ends of the pintle 8 are bent back upon themselves as at 10 to provide out-

wardly projecting U-shaped bearings for fitting the lateral edges 11 of the ash doorway to hold the pintle to position, as indicated in Figures 1 and 2.

The abutment extension 2 of the front 1 may be depressed, as at 12, to provide a means for facilitating engagement by finger or implement when it is desired to tilt the device to the lowered position indicated in Figure 1.

The ends 10 of the pintle provide a simple removable mounting for the device, making unnecessary the drilling of holes or the use of other means of attaching special bearings for the pintle 8 of the ash gate.

The pintle 8 may be mounted across the bottom of the doorway by first engaging one end 10 with an edge of the doorway, then tilting same and bringing the other end 10 down into engagement with the other edge of the doorway. The pintle may thus be mounted before the body of the gate is connected therewith by the ears 6 and rivets 9 or, by flexing one side 3 of the gate the same may be mounted after complete assembly.

When properly mounted the weight of the side wings 3 will be distributed rearwardly of the pivot pintle and cause the front 1 to close the ash doorway, with the abutment 2 against the top edge thereof, and effectively guard against inadvertent ash discharge.

The curves 4 serve to permit movement on the pivoted connection while providing for substantially complete lateral closure, by the side wings 3, the shoulders 5 serving to limit outward movement of the guard as indicated in Figure 2.

The numeral 13 is used to designate the ash door, and 14 the ash receiving pan when such is used.

It will be understood that when an ash pan 14 is used the side wings 3 work freely at each side thereof.

It has heretofore been the experience that, upon opening the ash door of a stove which has been permitted to operate over an extended period without ash removal, quite a quantity of ashes are inadvertently discharged upon the floor. This obviously results in unnecessary trouble in clearing the floor and is dangerous in that the spilled ashes frequently include live coals.

It will be quite obvious by reference to Figure 1, that my ash gate will effectively

overcome the above stated difficulty as it can be gradually opened and the ashes observed and attended to without any danger of inadvertent discharge thereof.

5 From the foregoing description, taken in connection with the accompanying drawing, it is thought the novel details of construction, the manner of use and the advantages of my invention will be readily apparent to 10 those familiar with the use of such devices.

What I claim is:—

1. A device of the class described mountable in a stove ash doorway having side edges, said device comprising a front and 15 ash guard side wings, means for providing a pivot hinge for the lower edge of the front, and means for removably mounting the pivot hinge providing means to engage the side edges of the doorway.

20 2. A device of the class described mountable in the ash doorway of a stove and comprising, a front having an abutment extension for engaging the top edge of the doorway to limit inward movement, sides extending 25 back into the doorway and adapted when the device is closed to hold it closed by the weight thereof and when the same is open to provide lateral ash guards, and a hinge pindle on which the device is mounted having 30 its opposite ends bent upon themselves to form U-shaped bearings for engaging the lateral edges of the ash doorway.

35 3. A device of the class described mountable in a stove ash doorway having side edges, said device comprising a front and ash guard side wings, hinge pindle bearings carried by the front at its lower edge, a hinge pindle upon which the lower edge of the front is hingedly mounted with the bearings 40 thereof loosely surrounding the hinge pindle, and means at the ends of the hinge pindle for detachably engaging the doorway edges to mount the said pindle.

45 4. A device of the class described mountable in the ash doorway of a stove and comprising, a front having an abutment extension for engaging the top edge of the doorway to limit inward movement, sides extending 50 back into the doorway and adapted when the device is closed to hold it closed by the weight thereof and when the same is open to provide lateral ash guards, a hinge pindle on which the device is mounted having its opposite ends bent upon themselves to form 55 U-shaped bearings for engaging the lateral

edges of the ash doorway, the said sides being curved along the top edge on an arc struck from the axis of the hinge pindle and having abutment shoulders for limiting outward movement of the device. 60

5. A new article of manufacture of the class described adapted to be mounted in the ash doorway of a stove and to be bent from a sheet of metal to comprise a closure front 65 having an upward extension for engaging the top edge of the ash doorway to limit inward movement, side wings adapted to extend back into the doorway in a manner for normally holding the device to the closed 70 position by the weight thereof and when moved outwardly to provide lateral ash guards, the said side wings each having an edge curved on an arc struck from the point on which the device is to be pivoted and an 75 abutment shoulder for limiting outward movement of the device, and the said front having bearing forming extensions adapted to be bent back upon and secured to the same for providing loose bearings, and a hinge 80 pindle loosely mounted in the bearings and detachably engaging the ash doorway side edges to provide pivotal mounting for the article.

6. A new article of manufacture of the 85 class described adapted to be mounted in the ash doorway of a stove and to be bent from a sheet of metal to comprise a closure front having an upward extension for engaging the top edge of the ash doorway to limit 90 inward movement, side wings adapted to extend back into the doorway in a manner for normally holding the device to the closed position by the weight thereof and when moved outwardly to provide lateral ash 95 guards, the said side wings each having an edge curved on an arc struck from the point on which the device is to be pivoted and an abutment shoulder for limiting outward movement of the device, and the said front having bearing forming extensions adapted 100 to be bent back upon and secured to the same for providing loose bearings, and a hinge pindle loosely mounted in the bearings and connected with the ash doorway edges to 105 provide pivotal mounting for the article, the said pindle having its opposite ends bent back upon themselves to form U-shaped portions for removably engaging the lateral edges of the ash doorway.

MICHAEL MILAZZO.
